UNITED STATES PATENT OFFICE

EDWARD W. MOEHLER, OF HOPKINS, MINNESOTA

EGG CARTON FILLER

Application filed October 8, 1930. Serial No. 487,314.

This invention relates to a removable collapsible filler for use in connection with egg trays, cardboard cartons and the like.

In carrying the inventive conception into practice, I have developed a simple and economical collapsible cardboard filler of a hill and dale type wherein the companion portions are collapsible in an accordionlike manner, to provide substantially V-shaped receptacles or saddles for reception of the eggs, the walls of said receptacles being provided with complementary openings to permit portions of the eggs to protrude therethrough in such a manner as to suspend the eggs in the carton and to avoid breakage.

In developing the idea, I have found it expedient and practical to provide a foldable apertured sheet or blank of cardboard having score or fold lines defining the companion portion whereby to permit expanding of the blank in a carton or box to provide the V-shaped channel-like receptacles for the eggs.

In addition, I provide partitioning pieces which constitute dividers for developing individual cells or pockets for the respective eggs.

The particular details which characterize this arrangement will become more readily apparent from the following description and drawings.

In the drawings:

Figure 1 is a top plan view of an ordinary cardboard carton provided with the improved filler designed in accordance with the invention.

Figure 2 is an end view thereof with the carton in section.

Figure 3 is a plan view of the foldable cardboard blank.

Figure 4 is a fragmentary perspective view showing the blank folded for insertion into the carton.

Figure 5 is a perspective view of one of the especially designed partitioning elements.

In the drawings, the reference character 6 in Figure 2 designates a box-like body portion of an ordinary egg carton and 7 represents the lid. The removable filler unit or insert is generally denoted by the numeral 8.

As before stated, this is formed from a single

blank of bendable cardboard of the form represented in Figure 3. As shown in Figure 3, the fold or score line 9 serve to define a plurality of pairs of companion walls or sectors 10 and 11.

These combined sectors 10 and 11 are provided with elongated openings 12 to accommodate the eggs. In addition I provide longitudinally elongated slots 13 which bridge the line 14 and which serve to accommodate the partition elements 15. Each partition element comprises a length of cardboard 16 provided at its ends with T-shaped extensions or heads 17. These heads 17 are designed to be interlocked with vertical slots 18 formed in the depending end walls 19 of the complete filler.

Incidentally, when the filler is bent up to the position shown in Figure 4, the walls 10 and 11 assume downwardly converging relationship and thereby provide V-shaped channel-like receptacles. When the partition pieces 16 are slipped up into the slots 13 they define individual egg pockets. It will be noted in this connection that the numerals 20 designate struck-out tongues which are arranged between the bight and saddle portions of the receptacles as shown in Figure 2 of the finished product.

Then too, on the upper edge of the elements 16 are V-shaped extensions 21 which fit into the crown portion of the so-called channel shaped receptacles. Thus, by slipping the eggs into the companion portions of the slots 12 they are suspended or saddled in place in a cushion-like manner.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice if desired.

I claim:

As a new product of manufacture, an egg carton filler comprising a collapsible card-

board blank formed into distinguishable sectors, said sectors functioning as walls, the end sectors being bent downwardly into vertical positions and the other sectors being bent into downwardly converging relationship to provide egg receiving channels, said other sectors being provided with egg holes and on opposite sides of the holes with partition slots, said holes and slots extending through the lower ends of the channels, partition pieces removably fitted in said slots and defining individual egg cells, the end sectors constituting depending walls and being provided with retaining slots, the end portions of said partition pieces being formed with vertically arranged T-shaped heads having interlocking detachable connection with said slots in the end sectors, the heads extending beyond the slots to provide spacers for engagement with the adjacent walls of a box, each partition piece being provided on the upper edge with V-shaped extensions nested in the crown portions of the adjoined channel forming sectors and being further provided near its bottom with outwardly bent spacing tongues arranged between the lower portions of the complementary sectors.

In testimony whereof I affix my signature.
EDWARD W. MOEHLE.
